(57) **CLAIM**

The ornamental design for a candle and container, as shown and described.

DESCRIPTION

FIG. 1 is a perspective view of a portion of a candle and container.

FIG. 2 is a bottom perspective view of the candle and container of FIG. 1.

FIG. 3 is a front view of the candle and container of FIG. 1.

FIG. 4 is a rear view of the candle and container of FIG. 1.

FIG. 5 is a left side view of the candle and container of FIG. 1.

FIG. 6 is a right side view of the candle and container of FIG. 1.

FIG. 7 is top view of the candle and container of FIG. 1; and, FIG. 8 is a bottom view of the candle and container of FIG. 1. The broken line showing of environmental structure in the figures is for illustrative purposes only and forms no part of the claimed design.
